(57) **CLAIM**

The ornamental design for a skin tag removal kit, as shown and described.

DESCRIPTION

FIG. 1 is a perspective view of a skin tag removal kit, showing the main part and the replaceable parts separately; FIG. 2 is a disassembled perspective view shown in FIG. 1 where two of the replaceable parts removed in the skin tag removal kit for clarity of the disclosure;

FIG. 3 is a perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.
